UNITED STATES PATENT OFFICE.

EDWIN H. BELL, OF CHICAGO, ILLINOIS.

ADJUSTABLE DERAILING DEVICE.

1,323,441.

Specification of Letters Patent.

Patented Dec. 2, 1919.

Application filed November 15, 1918. Serial No. 262,634.

To all whom it may concern:

Be it known that I, EDWIN H. BELL, a citizen of the United States, and a resident of Chicago, in the county of Cook and State of Illinois, have invented certain new and useful Improvements in Adjustable Derailing Devices; and I do hereby declare that the following is a full, clear, and exact description thereof, reference being had to the accompanying drawings, and to the letters of reference marked thereon, which form a part of this specification.

This invention relates to improvements in derailing devices and more particularly to an improvement upon the type of derailing device illustrated, described and claimed in the United States Patent No. 1,109,007, issued to George W. Nibbe, September 1st, 1914, wherein is disclosed a derailing device adapted to swing about an axis of rotation, and provided with means for vertical adjustment whereby the derailing device may be made to accommodate rails of different heights; and provided, also, with an operating link extending transversely under the rail in the usual manner.

In devices of this type, the derailing block member is relatively heavy, and when swung about its axis of rotation under the influence of the operating link, swings a relatively considerable distance away from the rail and through a considerable arc until the rock arm carrying at its outer end the derailing block, is arrested by the ties on the road bed,—said rock arm being at that time in substantially the same horizontal plane as the rail base. The weight of the rock arm and derailing head proper, and this swinging movement from the rail, tends somewhat to strain the pivotal connections. Again, when in this position and it is desired to swing the derailing head into proper position on the top of the rail, a very considerable strain has to be exerted, in actuating the operating link in overcoming the dead center.

The principal object of my invention, therefore, is to provide adjustable means on the rock arm whereby the extent of movement of the derailing head will be materially decreased, whereby the rock arm and derailing head will lie at an acute angle to the vertical axis of the rail when the derailing head is off the rail, whereby less power is required to actuate the operating link to restore the derailing head to the rail and

whereby the strain on the connections during the moving operation will be rendered negligible.

These and other objects of the invention are accomplished by providing means on the rocking arm adapted at the extreme point of the movement of the rock arm, to lie in a plane substantially parallel and in proximity beneath the rail base to contact therewith; thus said arm and rail base form a stop to limit the swing of the rock arm away from the rail.

I also provide adjustable means whereby the arresting device may be used in connection with an adjustable derailer.

In the drawings:

Figure 1 is a view in side elevation, of a derailing device embodying my invention.

Fig. 2 is a vertical section through the derailing device, in a plane indicated by the line 3—3 of Fig. 1.

Fig. 3 is a similar view showing a modification.

Referring now to that embodiment of my invention illustrated in the drawings, A indicates a rail attached to and supported upon ties 1, in the usual manner. The derailing device is shown as applied to the rail at a point between the two ties, where a channel 2 below the rail base is formed in the ballast or road bed to provide space for the parts of the device which are located below the level of the rail base.

The derailing device includes the usual derailing block 3, which is carried by a rock arm 4, a supporting and attaching member 5 by means of which the device is attached to the rail A and by which the rock arm 4 is rotatively carried; and an operating link 6 which extends transversely under the rail in the usual manner. The derailing block 3 is of any familiar or convenient construction, designed to catch the wheel flange and force the wheel as it rides upon the block to travel in a diagonal direction across the block from its inner to its outer edge in such manner as to derail the wheel. The formation of said block being of no particular interest in the present invention, further description of the same is unnecessary.

The attaching and supporting means 5 is provided with an upright flange 7 adapted for engagement with the outer face of the web of the rail, and provided with apertures 8 by means of which it may be attached to the rail. Said supporting mem-

ber is also provided with a base flange 9 for engagement with the top face of the rail base flange, and with longitudinally spaced lugs 10. These lugs 10 carry a non-rotative shaft 11 extending parallel to the rail A and constituting the member upon which the rock arm 4, connected to the derailing block 3, is hinged. Each of the lugs 10 has a vertical, elongated slot 12, of a width substantially equal to the diameter of the shaft 11, the vertical sides of said slot being provided with vertically spaced notches or key-ways 13, adapted to receive oppositely placed keys 14, 14, fixed to the shaft 11. There are two pairs of such keys fixed to the shaft. Manifestly, the shaft may be adjusted vertically in the slot 12 by shifting the keys 14 in different key-ways.

15 indicates horizontally spaced lugs on the rock arm 4, which project downwardly below the level of the shaft 11 and which are provided with apertures for the reception of a pivot bolt or nut 16 by means of which the link 6 is operatively connected with the arm 4. The longitudinal movement of the link 6 produced by suitable mechanism placed on the outside of the rail opposite the rail A operates to swing the arm 4 so as to apply or remove the derailing block 3 to or from the rail, as desired, in the usual manner.

Upon the rock arm 4 and projecting downwardly below the level of the shaft 11, is an arresting arm 17 suitably apertured to carry a screw threaded bolt 18. The exact angle at which this arm 17 will project with respect to the plane of general direction of the arm 4 will vary according to the style or type of derailing device to which it is applied, and the location of the non-rotative shaft 11 with respect to the rail base; the object being to so shape the arm 17 that its contact face 19 will, when the arm 4 is swung away from the rail A, lie beneath and substantially parallel to the bottom of the supporting base 20 of the rail A, and so that the end 21 of the adjusting bolt 18 will contact with said rail base 20. By moving the bolt 18 in and out, variations in the adjustment of the shaft 11 to accommodate rails of different heights, will be compensated for.

Where the derailing device is not adjustable, the shape of the projecting arm 17 may be such that the surface 19 thereof may contact with the base 20 of the rail; but it is more desirable even in such instances, to use the adjusting bolt 18 to cover variations in the manufacture of parts, as well as the wear.

It will thus be seen that the rail base 20 acts as a stop to contact with a projection on the moving or rocking arm 4, and to arrest the movement of the latter when directed away from the rail A; and it will

also be seen that adjustable means is provided by the bolt 18, whereby the throw of the arm 4 may be regulated to suit the various conditions that may be encountered in practice.

While I have shown, in Fig. 2, that the arm 17 is cast integral with the rock arm 4, it will be apparent that such arm may be applied to existing devices. Thus I have shown the modification in Fig. 3 whereby the arm 17 is provided with an extension 22 having suitable apertures to receive bolts 23 whereby the arm 17 may be bolted to the rock arm 4. By this means my improvement may be applied to derailing devices already in use, by the simple expedient of drilling and tapping suitable holes in the rock arm 4 adapted for engagement with the bolts 23. This and other details of mechanical construction and arrangement I desire to have comprehended within the scope of my invention.

I claim as my invention:

1. In a derailing device, the combination of a derailing block, means for operatively supporting said derailing block for motion to and from derailing position, and means movable with the derailing block, adapted to arrest it by contact with the rail base.

2. In a derailing device, the combination of a derailing block, means for operatively supporting said derailing block for motion to and from a derailing position, and adjustable means on said supporting means adapted to arrest the motion by contacting with the rail base.

3. In a derailing device, the combination of a derailing block, an arm fixed thereto, means for operatively attaching said arm in a position adjacent to a rail, means for vertically adjusting the axis of rotation of said arm to accommodate rails of different heights and means for arresting the rotative movement of the arm.

4. In a derailing device, the combination of a derailing block, an arm fixed thereto, means for operatively attaching said arm in a position adjacent to a rail, means for vertically adjusting the axis of rotation of said arm to accommodate rails of different heights and adjustable means for arresting the rotative movement of the arm.

5. In a derailing device, the combination of a derailing block, a rock arm fixed thereto, a supporting member adapted to be attached to the rail, means whereby the rock arm is rotatively connected to said supporting member and means on the rock arm adapted for co-operation with the rail base to arrest the rotative movement of the rock arm.

6. In a derailing device, the combination of a derailing block, a rock arm fixed thereto, a supporting member adapted to be attached to the rail, means whereby the rock

arm is rotatively connected to said supporting member and means on the rock arm adapted for coöperation with the rail base to arrest the rotative movement of the rock arm, said means comprising a lug or arm projecting in a direction away from the derailing head.

7. In a derailing device, the combination of a derailing block, a rock arm fixed there-to, a supporting member adapted to be attached to the rail, means whereby said rock arm is rotatively connected to said supporting member, means for vertically adjusting the axis of rotation of said arm to accom-

modate rails of different heights, a lug on 15 said rock arm projecting below the level of the axis of rotation, a bolt adjustably mounted on said lug and adapted in coöperation with the rail base, to limit the rotative movement of the rock arm.

In testimony, that I claim the foregoing as my invention I affix my signature in the presence of two witnesses, this 9th day of November A. D., 1918.

EDWIN H. BELL.
